(57) **CLAIM**

The ornamental design for a barbecue assembly, as shown and described.

DESCRIPTION

FIG. 1 a front view of a barbecue assembly in an unfolded state;

FIG. 2 is a rear view of the barbecue assembly;

FIG. 3 is a left side view of the barbecue assembly;

FIG. 4 is a right side view of the barbecue assembly;

FIG. 5 is a top view of the barbecue assembly;

FIG. 6 is a bottom view of the barbecue assembly;

FIG. 7 is a perspective view of the barbecue assembly;

FIG. 8 is a first perspective view of the barbecue assembly in a collapsed state;

FIG. 9 is a second perspective view of the barbecue assembly in a collapsed state;

FIG. 10 a front view of a grill element of the barbecue assembly without supporting portion, shown in isolation;

FIG. 11 is a rear view of the grill element of the barbecue assembly, shown in isolation;

FIG. 12 is a left side view of the grill element of the barbecue assembly, shown in isolation;

FIG. 13 is a right side view of the grill element of the barbecue assembly, shown in isolation;

FIG. 14 is a top view of the grill element of the barbecue assembly, shown in isolation thereof;

FIG. 15 is a bottom view of the grill element of the barbecue assembly, shown in isolation;

FIG. 16 is a first perspective view of the grill element of the barbecue assembly, shown in isolation; and,

FIG. 17 is a second perspective view of the grill element of the barbecue assembly, shown in isolation.

The broken lines depict portions of the barbecue that form no part of the claimed design. The broken lines immediately adjacent the shaded areas represent the bounds of the claimed design.

1 Claim, 17 Drawing Sheets
